UNITED STATES PATENT OFFICE.

FRANK D. PEARNE, OF GRAND ISLAND, NEBRASKA.

RELAY.

SPECIFICATION forming part of Letters Patent No. 674,540, dated May 21, 1901.

Application filed December 11, 1900. Serial No. 39,580. (No model.)

To all whom it may concern:

Be it known that I, FRANK D. PEARNE, a citizen of the United States, residing at Grand Island, in the county of Hall and State of Nebraska, have invented a new and useful Relay, of which the following is a specification.

This invention relates to relays in general, and more particularly to that class including a plurality of pairs of contacts which are adapted to be made and broken upon the movement of a polarized relay-armature. The present relay is specially designed for use in connection with the type-writer-telegraph system forming the subject-matter of a separate application for patent filed by me on the 11th day of December, 1900, Serial No. 39,577. This relay forms one of the line-relays, one object of the invention being to provide a construction wherein the armature which makes and breaks the several circuits will be held delicately poised above the actuating-magnets and will be returned to normal position without the use of springs, further objects and advantages of the invention being evident from the following description.

In the drawings forming a portion of this specification, and in which like characters of reference indicate similar parts in the several views, Figure 1 is a front elevation of the relay with the armature thereof in normal position. Fig. 2 is a side elevation of the relay with a portion of the field-magnet broken away to show the positions of two of the contacts. Fig. 3 is an elevation showing a modification including a different shape of field-magnet and a different arrangement of contacts.

Referring now to the drawings, the present relay comprises an insulating-base 5, upon which are mounted spaced supports 6 and 7, which hold the field-magnet 8 in an elevated position above the base. This field-magnet, as shown, is in the form of a bar 9, one end of which is bifurcated to form arms 10 and 11, which are bent outwardly in opposite directions and in a common plane at right angles to the body of the bar, after which they are bent downwardly to lie parallel and are then bent toward each other to form the pole-pieces 12 and 13 of like polarity. Taking the upper end of the stem of the bar as a north pole,

(marked N,) then the two poles at the ends of the arms are both south poles, (marked S.) The poles 12 and 13 are spaced apart a distance sufficient to receive between them the 55 armature, which consists of a straight bar 14, having an upwardly-directed stem 15 standing at right angles to the bar, and at the upper end of which is a contact-piece 16. The ends of the bar 14 lie in close proximity to 60 the poles 12 and 13, and on the upper faces of the end portions of this bar are fixed contact-plates 17 and 18 for a purpose which will be presently explained. With this arrangement it will be noted that the lines of force 65 from the north pole at the upper end of the body of the magnet will pass downwardly at both sides of the body to the stem 15 of the armature. They will pass through the stem to the bar 14, where they will divide and will 70 pass longitudinally of the bar and from the ends of the bar to the poles 12 and 13, the result being that the armature will be held normally at rest and with the axis of the bar 14 coinciding with a line connecting the centers 75 of the poles 12 and 13, the armature being held pivotally to prevent dropping thereof.

The pivotal mounting of the armature consists of a spindle 17', passed transversely through the bar at the base of the stem of the 80 armature, and the ends of which spindle are tapered and are engaged in recesses in the ends of set-screws 18' and 19. The set-screw 18' is engaged with a post 20 at one side of the armature, and the set-screw 19 is engaged with 85 a post 21 at the opposite side of the armature. The post 21 is continued above the set-screw and has an arm 22 at its upper end, which projects forwardly and over the upper end of the stem 15 of the armature. In this forwardly-projecting arm 22 is engaged a contact-screw 23, in position for normal contact by the contact-piece 16. When the armature is rocked, however, the contact-piece 16 is moved from engagement with the screw and 90 a circuit including the screw and contact-piece is broken. The set-screw 19 is directly engaged with an insulating-bushing 24 in the post 21, while screw 18' is engaged directly with the post 20, which latter has a binding-post 25 at its base for engagement of a circuit-wire. The post 21 has also a binding-post 26

engaged therewith for connection of a circuit-wire, and when the armature is in normal position these two binding-posts are in circuit.

The posts 27 and 28 are mounted on the base 5, and the upper ends thereof extend forwardly and over the ends of the bar 14 of the armature and carry contact-screws 29 and 30, respectively, which are adapted for alternate contact by the contact-plates on the armature 10 when the armature is rocked. The posts 27 and 28 are provided with binding-posts 31 and 32, respectively, for attachment of circuit-wires. Thus it will be seen that when the armature is rocked in one direction its contact 15 with screw 23 is broken and contact with screw 29 is made and that when the armature is rocked in an opposite direction from normal contact with screw 23 is broken and contact with screw 30 is made, throwing the posts 20 26, 29, and 30 alternately into circuit with the post 25. To thus rock the armature, which is of course polarized by the action of the field-magnet, an electromagnet is provided including the two spools 33 and 34, having the 25 pole-pieces 35 and 36. When current is sent through the windings of this electromagnet in one direction, one pole thereof is north and the other south, the north pole repelling the adjacent end of the armature and the south pole attracting its adjacent end of the armature. When the direction of flow of current 30 is reversed, the polarity of the magnet is reversed and the opposite ends of the armature are attracted and repelled, causing the armature to rock in an opposite direction. When 35 no current flows, the armature stands in normal position, above referred to.

In Fig. 3 of the drawings there is shown a construction which is the same in all respects 40 as that just described, with the exception that the body portion of the field-magnet (shown at 40) is taken downwardly to lie between the arms 41 and 42. The armature 43 has the same construction, excepting that the bar 44 thereof is longer than in the former instance to permit of placing the contact-plates 45 and 46 on the under sides of the ends thereof beyond the spools of the electromagnet and the contact-screws 47 and 48 are passed upwardly 45 through the laterally-extending arms of the posts 49 and 50 for engagement by the contacts when the armature is rocked. The operation is the same as in the former instance; but by bringing the poles of the field-magnet 55 in closer proximity the field of force thereof is of course intensified.

It will be understood that in practice various other modifications of the invention may be made and that any suitable materials and 60 proportions may be used for the various parts without departing from the spirit of the invention.

What is claimed is—

1. A relay comprising a field-magnet having 65 opposing like poles and an unlike pole

spaced therefrom, an armature comprising a member adapted to aline with the like poles and a member for projection in the direction of the unlike pole, and an electromagnet disposed adjacent to the armature to rock it. 70

2. A relay comprising a field-magnet having opposing poles of like polarity and an unlike pole spaced therefrom, an armature comprising a member disposed to aline with the like poles and a member to project in the direction of the unlike pole, said armature being pivotally mounted, and a bipolar electromagnet disposed with its poles adjacent to the first member of the armature at opposite sides of the pivot of the latter, to rock the armature. 75

3. A relay comprising a field-magnet having opposing like poles and an unlike pole equidistant from the like poles, an armature comprising a bar disposed in line with the like poles and a stem extending in the direction of the unlike pole, and means for rocking the armature in the field of force of the magnet. 85

4. A relay comprising a field-magnet having a divided field of force, an armature including members disposed to approximately coincide with the axes of the divisions of the field of force, and means for rocking the armature in the field of force. 90

5. A relay comprising a field-magnet consisting of a body portion having one end bifurcated to form like poles, the bifurcations being bent outwardly and then inwardly in axial alinement, an armature pivoted in the field of the magnet and including a bar in axial alinement with the like poles and a stem lying in the direction of the opposite end of the body of the field-magnet, and means for rocking the armature in the field of said magnet. 95

6. A relay comprising a field-magnet having a divided field of force, an armature including members disposed to approximately coincide with the axes of the divisions of the field of force, contacts carried by the members of the armature additional contacts for engagement by the contacts upon the armature, and means for rocking the armature in the field of the field-magnet to engage its contacts. 105

7. A relay comprising a field-magnet having a divided field of force, a pivoted armature including a main bar and a stem disposed to approximately coincide with the axes of the field of force, a contact carried by the stem, contacts carried at the ends of the bar, 110 fixed contacts for engagement by the contacts of the armature, and means for rocking the armature in the field of the field-magnet. 115

In testimony that I claim the foregoing as my own I have hereto affixed my signature in 120 the presence of two witnesses.
